STEPLADDER

Albert A. Schramm, Chicago, Ill.

Application September 10, 1930, Serial No. 480,919

15 Claims. (Cl. 228—38)

This invention relates to ladders and is illustrated as embodied in a folding stepladder which is so constructed that the worker may have an unusually large step or platform on which to work and may move the upper steps out of his way.

The ladder may conveniently include folding cross-members or beams and a sliding sectional platform which may be drawn out any desired extent.

One object of the invention is to provide a ladder which is safer than any heretofore known.

Another object of the invention is to provide a folding ladder in which the steps are deep enough to enable a user to have a full, firm and shiftable footing thereon, as well as to stand near the center of the ladder even when near the bottom thereof to make the ladder less easily tipped over.

Another object of the invention is to provide a ladder in which the steps above the one being stood upon may be shifted out of the way.

A further object of the invention is to provide a ladder which will be less tiresome to use.

Other objects of the invention will appear from the following description, drawings and claims.

In the drawings, in which like numerals are used for similar parts throughout—

Figures 1 and 2 are vertical sectional views of the ladder in its operative and folded positions respectively;

Figure 3 is a front elevation of the ladder;

Figure 4 is a plan view of the top of the ladder;

Figure 5 is a detail sectional view showing one of the sliding platform steps and connecting parts;

Figure 6 is a horizontal section of the detail shown in Figure 5, taken along the line 6—6 of Figure 5;

Figure 7 is a detail vertical section taken along the line 7—7 of Figure 5; and

Figure 8 is a fragmentary view similar to Figure 1, but of a modification.

Although this invention may take many forms, only two have been chosen for illustration in the drawings. Both forms include two front legs or uprights 10, and two back legs or uprights 12. The legs 10 are pivoted to the top-side members 14 which are rigidly secured to the back legs 12 as by the rivets 16. The top-side members are composed of the two inner plates 18 and the U-shaped member 20. To give the legs of the U the desired rigidity, its

base is bent over as indicated at 22 in Figure 1. To further reinforce the top construction, and therefore the ladder as a whole, a metal bar 24 is passed across the top and rigidly fastened to each side member as by the nuts 26.

The front legs are properly spaced through the rest of their length by the bottom step 28 and spacers 29. The back legs are reinforced by the diagonal strips 30 and the U-shaped strips 31. The latter extend along and are secured to the sides of the legs as at 32 to prevent them from twisting.

The proper spacing between front and back legs is secured by the folding beams, each of which has the two parts 34 and 36 hinged together by hinge 38, which will permit the joint to be bent upwardly only. The beam parts 36 are pivoted to the front legs 10 as shown at 40, and the beam parts 34 are pivoted at 42 to plates 44 which are riveted to back legs 12.

When the two beam members 34 and 36 are in operative position they form a continuous level beam as shown in Figure 1. The inside top edges of these beams are cut away to form the recess 46.

Platforms are formed between the beams by laying slats 48 in the recesses 46 to rest on the bottom faces thereof. These slats are mounted on leather straps 50 so that they may slide together along the beams. Of course, any other flexible platform may be provided if desired. A retaining strip 51 is attached to project over the recess 46 to keep the slats in place. Sufficient tolerance is left to insure easy movement of the slats. As illustrated, the platforms preferably have a depth, i. e., a front to back width, greater than the length of a man's shoe, to permit the user to stand or turn around on it with ease and safety.

The front slat 48 is provided with suitable reinforcing means 52 since it may occasionally be subjected to abnormal weights. The member 52 also serves as a handle. There may be provided a suitable catch for holding the platform in the desired position. This catch, as illustrated, comprises the washer 54 screwed to the front beam 36, in combination with a corresponding recess 58 in the front slat. When it is desired to slide the platform out of the way, it is merely necessary to raise the front slat clear of the washer 54 and push it back.

When it is desired to fold the ladder or to get a step entirely out of the way, the step is shoved back partially off of the beam member as shown in Figure 2. To facilitate the movement of the

110

slats around the corner the beam members 34 are beveled at their back ends, and the back one of the slats 48 is beveled along its back-top edge.

To hold the slats in position ready to be drawn up onto the beams, pairs of racks 60 are provided. These racks comprise the guide members 62 (Figure 6) and the fillers 64 which position the slats endwise to enter the recesses 46.

Although the top step 66 may be made in the same manner, a preferred embodiment has been shown. Here the slats 68 are permanently attached to the cross-members 70 which are pivoted at 72 to the back legs. When used as a step it is placed in the position shown in full lines in Figure 1, in which case its front end is supported by suitable plates or angle irons 74. The step may be swung over to the position shown in dotted lines to be used for a shelf, in which case it is held in horizontal position by the upper horizontal brace 31. Suitable means such as a spring friction member may be provided for holding the step in vertical position between the back legs when it is not wanted and particularly when the ladder is folded.

25 A suitable chain 79 is provided, connecting the upper and lower back beam members 34 so that both may be moved simultaneously. This should be connected near the bottom of the members so as not to interfere with closing the ladder.

30 To provide a suitable handle and to further insure against twisting of the back legs an additional brace 80, or more if desired, may be secured across the forward edges of these legs.

To prevent undue wear, and especially elongation of the various pivot holes, suitable bushings and wear plates are preferably provided. For example, copper bushings are provided for the pivot holes at 40 and 42 where the front and back beam members have their pivotal support.

40 The operation of this ladder is as follows. To set up for use, the front and back legs are spread apart, and the beam members straightened down unless they moved all the way down when the ladder was spread. The bottom platform (next to bottom step) is then pulled out and secured in its forward position. The second platform is left in its back position unless and until it is needed when it is pulled forward to the desired position.

45 When the upper platform is back, the worker can have the use of the entire lower platform, so that he has a firm, safe and untiring footing. The upper platform can be left in sort of a half-way position where it can be used if desired and yet is not much in the way. Unless the top step is wanted it is either left in its vertical position or it is turned back to be used as a shelf. To fold the ladder, the platforms are slid back beyond the hinges 38 and the two upper beams are broken by raising the central portions. This also breaks the lower beams, as the upward movement is transmitted to them through the chain 79. By merely tilting the ladder it then collapses by its own weight. The bottom slats may be secured permanently in place by so spacing them that no slat lies across the joint between the two parts of the beams, as shown in Figure 8.

55 It is thus seen that the ladder not only is more safe, satisfactory and efficient in use than any heretofore known but it is also as easily folded as any.

70 I claim:

1. A folding ladder including in a single active position four relatively hinged legs, folding beams between and pivotally mounted at their ends to said legs, a step slidably mounted on said beams,

and a platform of more than six inches depth from front to back located as another step below said slidably mounted step; said slidably mounted step being guided from its customary useful position to an out-of-the-way position.

80

2. A folding ladder including a plurality of relatively hinged legs, a pair of folding beams between and pivotally mounted at their ends to said legs, a platform slidably mounted on said beams, and a rack into which said platform may be partially slid, said rack being mounted on the two rear legs of the ladder adjacent said folding beams.

85

3. A folding ladder including a plurality of relatively hinged legs, a pair of folding beams between and pivotally mounted at their ends to said legs, a flexible platform slidably mounted on said beams, and a rack into which said platform may be partially slid, said rack being mounted on the two rear legs of the ladder adjacent their folding beams.

90

4. A folding ladder including a plurality of relatively hinged legs, a pair of folding beams between and pivotally mounted at their ends to said legs, a platform slidably mounted on said beams, and a catch for preventing the accidental moving of said platform with respect to said ladder.

95

5. A folding ladder including a plurality of relatively hinged legs, a pair of folding beams between and pivotally mounted at their ends to said legs, a platform slidably mounted on said beams, and a projection on said beam, said platform being adapted to engage said projection and to be released therefrom by lifting upwardly.

105

6. A folding ladder including a plurality of relatively hinged legs, an upper set and a lower set of folding beams between and pivotally mounted at their ends to said legs, a platform permanently attached to the lower beams but so constructed and spaced as not to interfere with the folding of the beams, and a platform slidably mounted on the upper beams so that it can be slid out of the way of a person using the lower platform and to a position where it will not interfere with folding of the upper set of beams.

110

7. A folding stepladder having relatively hinged legs and pairs of folding beams extending between said legs pivotally mounted at their ends to said legs at two elevations; a two-part platform supported by said lower beams, one part being permanently secured on each side of the folding joint; a platform slidably mounted on the upper beams and slidable to a position across the folding joint in said beams and to a position entirely behind said joint; and a third platform above said beams pivotally mounted to the rear legs of the ladder and movable to form a step within said ladder and alternatively a shelf behind said ladder.

120

8. A ladder including four legs relatively hinged in pairs, a pair of folding beams between and pivotally mounted at their ends to said legs, and a step shiftably mounted on said beams, a platform of more than six inches depth from front to back located as another step below said shiftable step; said shiftably mounted step being guided from its customary useful position to an out-of-the-way position.

130

9. A stepladder including a plurality of relatively hinged legs, two pairs of folding beams between and pivotally mounted at their ends to said legs, a platform of more than eight inches depth from front to back attached to the ladder and mounted on each pair of folding beams one above the other, the upper platform being shiftably mounted on each pair of folding beams.

145

150

- mounted on said beams and so constructed and guided that it may be moved from its usual operative position while the legs supporting it remain in their fully opened position to provide additional leg room above the lower platform. 5
10. A folding multiple platform stepladder including a pair of front supporting legs and a pair of rear supporting legs, the pairs being relatively hinged at the top, and two platforms attached to and supported by said ladder one above the other each of a comfortable depth of more than about eight inches; the lower of said platforms being supported on a set of divided horizontal folding beams each pivotally mounted at its ends to a front leg and a rear leg of the ladder, and the upper of said platforms being supported jointly by said front and rear legs and shiftably mounted and so constructed that it may be moved from its usual operative position while the legs supporting it remain in their fully opened position; said platform being guided to such a position as to provide additional leg room above the lower platform. 20
11. A folding ladder including a plurality of relatively hinged legs, an upper set and a lower set of folding beams between and pivotally mounted at their ends to said legs, a platform permanently attached to the lower beams but so constructed and spaced as not to interfere with the folding of the beams, and a platform shiftably mounted on the upper beams so that it can be shifted and when shifted is guided to a position out of the way of a person using the lower platform and where it will not interfere with folding of the upper set of beams. 30
12. A folding, multiple platform stepladder including a pair of front supporting legs and a pair of rear supporting legs, the pairs being relatively hinged at the top, and two platforms supported by said ladder one above the other; each of said platforms being supported by a pair of divided horizontal folding beams each pivotally mounted at its ends to a front and a rear leg of the ladder, and means connecting the upper beam and the lower beam, said means being attached to each beam near its point of folding and being so constructed as to limit the separation of said points to the distance at which they are located when the ladder is opened and the beams unfolded, and said means being so
- constructed as to permit said points to move closer than said distance. 13. A folding, multiple platform stepladder including a pair of front supporting legs and a pair of rear supporting legs, the pairs being relatively hinged at the top, and two platforms supported by said ladder one above the other; each of said platforms being supported by a pair of divided horizontal folding beams each pivotally mounted at its ends to a front and a rear leg of the ladder, and means connecting the upper beam and the lower beam, said means being attached to each beam near its point of folding and being so constructed as to limit the separation of said points to the distance at which they are located when the ladder is opened and the beams unfolded, and said means being sufficiently flexible to permit said points to move closer together than the distance stated. 80
14. A stepladder having a plurality of legs, a plurality of steps secured at least indirectly to some of said legs and supported by some of said legs and located one above another according to customary spacing; at least one of said steps other than the top step being in the form of a platform having a depth from front to back of over six inches, and the step above said platform being shiftable, independently of its vertical supports, from its customary useful position above and slightly to the rear of the front of said platform, and being guided in its movement from said position to a position substantially back of said platform so that the space above said platform is substantially unobstructed by said step. 85
15. A stepladder having a plurality of legs, a plurality of steps including upper steps and a lower step secured at least indirectly to some of said legs and supported by some of said legs and located one above another according to customary spacing; at least one of said upper steps being shiftable, independently of its vertical supports, from its customary useful position above and slightly to the rear of the front of said lower step, and being guided in its movement from said position to a position substantially further back so that a space deep from front to back above said lower step is substantially unobstructed by said upper step. 90
16. A stepladder having a plurality of legs, a plurality of steps secured at least indirectly to some of said legs and supported by some of said legs and located one above another according to customary spacing; at least one of said upper steps being shiftable, independently of its vertical supports, from its customary useful position above and slightly to the rear of the front of said lower step, and being guided in its movement from said position to a position substantially further back so that a space deep from front to back above said lower step is substantially unobstructed by said upper step. 95
17. A stepladder having a plurality of legs, a plurality of steps secured at least indirectly to some of said legs and supported by some of said legs and located one above another according to customary spacing; at least one of said upper steps being shiftable, independently of its vertical supports, from its customary useful position above and slightly to the rear of the front of said lower step, and being guided in its movement from said position to a position substantially further back so that a space deep from front to back above said lower step is substantially unobstructed by said upper step. 100
18. A stepladder having a plurality of legs, a plurality of steps secured at least indirectly to some of said legs and supported by some of said legs and located one above another according to customary spacing; at least one of said upper steps being shiftable, independently of its vertical supports, from its customary useful position above and slightly to the rear of the front of said lower step, and being guided in its movement from said position to a position substantially further back so that a space deep from front to back above said lower step is substantially unobstructed by said upper step. 105
19. A stepladder having a plurality of legs, a plurality of steps secured at least indirectly to some of said legs and supported by some of said legs and located one above another according to customary spacing; at least one of said upper steps being shiftable, independently of its vertical supports, from its customary useful position above and slightly to the rear of the front of said lower step, and being guided in its movement from said position to a position substantially further back so that a space deep from front to back above said lower step is substantially unobstructed by said upper step. 110
20. A stepladder having a plurality of legs, a plurality of steps secured at least indirectly to some of said legs and supported by some of said legs and located one above another according to customary spacing; at least one of said upper steps being shiftable, independently of its vertical supports, from its customary useful position above and slightly to the rear of the front of said lower step, and being guided in its movement from said position to a position substantially further back so that a space deep from front to back above said lower step is substantially unobstructed by said upper step. 115
21. A stepladder having a plurality of legs, a plurality of steps secured at least indirectly to some of said legs and supported by some of said legs and located one above another according to customary spacing; at least one of said upper steps being shiftable, independently of its vertical supports, from its customary useful position above and slightly to the rear of the front of said lower step, and being guided in its movement from said position to a position substantially further back so that a space deep from front to back above said lower step is substantially unobstructed by said upper step. 120
22. A stepladder having a plurality of legs, a plurality of steps secured at least indirectly to some of said legs and supported by some of said legs and located one above another according to customary spacing; at least one of said upper steps being shiftable, independently of its vertical supports, from its customary useful position above and slightly to the rear of the front of said lower step, and being guided in its movement from said position to a position substantially further back so that a space deep from front to back above said lower step is substantially unobstructed by said upper step. 125
